UNITED STATES PATENT OFFICE.

TONY CHOLIN, OF CHINOOK, MONTANA.

GEARING-LUBRICATOR.

1,156,664.

Specification of Letters Patent. Patented Oct. 12, 1915.

Application filed June 9, 1913. Serial No. 772,614.

To all whom it may concern:

Be it known that I, TONY CHOLIN, a citizen of Canada, residing at Chinook, in the county of Blaine and State of Montana, have invented certain new and useful Improvements in Gearing-Lubricators, of which the following is a specification.

This invention relates to improvements in gearing lubricators and more particularly to devices of this class adapted to be applied to traction engines and the like.

My invention contemplates the provision of means carried by the engine and operatively associated with the exhaust pipe from which it receives and utilizes the waste oil coming from the engine cylinder to lubricate the running parts of the machine; means for increasing the force of the exhaust are also provided thereby affording a method of blowing dust away from the oiled parts.

With the foregoing and other objects in view the invention consists in the combination and arrangement of parts to be herein-after fully described in the following specification, pointed out in the claim and illustrated in the accompanying drawing which forms a part of said specification and in which the figure is a side elevation of a traction engine provided with my improved lubricator.

1 is the engine cylinder and 2 a suitable connection leading therefrom to the exhaust pipe 3 which may be provided with a cut-off valve 4 by which said exhaust may be regulated. To the exhaust

pipe 3 the oil and blow pipe 9 is connected by a T-coupling, or other suitable means, and said blow pipe is preferably of less diameter than the exhaust pipe.

6 is a stop valve by means of which the exhaust and flow of waste oil through the blow pipe may be regulated and said blow pipe is further provided with the blow stem 10 connected thereto by elbows 11, said stem being positioned back of the pinion gear 45 7 and large gear 8 that meshes with said pinion gear. In operation the valves 4 and 6 may be used to regulate the force of the exhaust through the blow stem 10 upon the gearing thus lubricating it and at the same 50 time blowing away any dust or other foreign matter that may adhere thereto before the same can work into the working parts of the machine.—

What is claimed is:

A lubricator for engines of the type described, including an exhaust-pipe leading from the engine-cylinder, said exhaust-pipe having two branches, a controlling valve in each branch, an element to be lubricated, and one of said branches adapted to discharge on said element. 55 60

In testimony that I claim the foregoing as my own I have hereto affixed my signature in the presence of two subscribing witnesses. 65

TONY CHOLIN.
